UNITED STATES PATENT OFFICE

KARL DAVIS ROBINSON, OF NEW YORK, N. Y., ASSIGNOR TO BARRETT & COMPANY, A CORPORATION OF NEW JERSEY

DESIGN FOR LEATHER OR SIMILAR ARTICLE OF MANUFACTURE

Application filed May 3, 1932. Serial No. 43,700. Term of patent 14 years.

To all whom it may concern:

Be it known that I, KARL DAVIS ROBINSON, a citizen of the United States, residing in the city and State of New York, have invented a new, original, and ornamental Design for Leather or Similar Article of Manufacture, of which the following is a specification, reference being had to the accompanying drawing, forming part thereof.

In the drawing:

The single figure is a plan view of a piece of leather showing my new design within the hexagonal area outlined by the points of the

six arrows shown in the figure; the points of the arrows indicate the corners of the hexagon. In the drawing, this unit of the design is shown repeated over the surface of the leather in the relation indicated by the extension of the figure beyond the hexagonal area.

I claim:

The ornamental design for leather or similar article of manufacture substantially as shown and described.

New York, N. Y., April 28th, 1932.

KARL DAVIS ROBINSON.
